United States Patent Office

Des. 204,591
Patented May 3, 1966

204,591

LIQUID DISPENSER

Henry Richard Landis, 5200 Stony Creek Drive, Oak
Lawn, Ill., and Thomas E. Wright, 6862 Lode Drive, Worth, Ill.

Filed Apr. 23, 1965, Ser. No. 84,932

Term of patent 14 years

(Cl. D2—3)

Fig. 2

Fig. 3

The undisclosed side of the liquid dispenser is substantially the same in appearance as the side shown.

We claim:

The ornamental design for a liquid dispenser, as shown and described.
